W. LEATHERS

STEAM POWER PLANT FOR AIRPLANES

Filed Dec. 26, 1919

INVENTOR

Hard Leather

UNITED STATES PATENT OFFICE.

WARD LEATHERS, OF HAWORTH, NEW JERSEY.

STEAM-POWER PLANT FOR AIRPLANES.

Application filed December 26, 1919. Serial No. 347,386.

To all whom it may concern:

Be it known that I, WARD LEATHERS, a citizen of the United States, resident of Haworth, county of Bergen, State of New Jersey, have invented new and useful Steam-Power Plants for Airplanes.

The object of my invention is to furnish a simple and promptly flexible means of handling a steam cycle. A further object 10 of my invention is to make a plant which may be controlled by the mere operation of a throttle. And a further object is to utilize the full boiler energy in producing more pressure before it is passed to the main 15 prime mover.

I do not wish to restrict my invention to an airplane plant since it has many other obvious uses.

In order to more clearly illustrate my invention I have appended a sheet of drawings 20 in which

Figure 1 is a longitudinal diagram of an aeronautical steam power plant.

Figure 2 is a sectional view of a reduction 25 or safety valve.

In Figure 1, 1 is a prime mover preferably a steam turbine which drives a propeller 2. The turbine obtains its motive fluid through the pipe 3 from the boiler 4. The boiler 4 is a steam boiler preferably of the flash type. 5 is a secondary prime mover which runs the air pump or blower 6, the water pump 7, and the fuel pump 8. Air from the pump 6 is forced through the pipe 9 to meet the fuel pumped by the pump 8 through the pipe 10 to the boiler, as illustrated in Figure 1. Fuel is obtained from a supply not shown at 11. The water pump 7 obtains water from the condenser 12 into 30 which the main prime mover exhausts through the passage 13. The water is obtained through the pipes 14 and 15 and is pumped into the boiler at 16. 17 is a check valve which prevents pressure in the combustion chamber passing out through the blower 6 when the same is idle, and forced draught is furnished by the starter.

18 is a reduction valve similar in operation to a safety valve. When the boiler pressure 40 exceeds a predetermined pressure the valve automatically opens and furnishes fluid to the turbine.

Motive fluid at boiler pressure is obtained through the pipe 19 and admitted to the 45 prime mover 5 by a throttle 20.

21 is an exhaust stack for the gaseous products of combustion.

Air pump 29, water pump 32 and fuel pump 33 furnish one of several simple means of starting. The hand blower 29 driven by a crank 30 or other means furnishes air for combustion. This may as readily be a supply of compressed air, or the pump or blower 29 may be motor driven if desired. 31 is a check valve corresponding in purpose to 17 in Figure 1. 32 is a water pump and 33 a fuel pump which may be operably connected to 29 or other means of furnishing the draught. 34 is a storage battery connected to the primary coil of a spark coil 35. The circuit is established by a contact 36. The secondary of the coil 35 is connected by means of the wires 26 to a spark plug in the boiler, not shown. A handle 38 is connected by suitable 50 means 27 to the throttle 20.

It is evident that the starting and controlling devices shown may be removed from the power plant shown in Figure 1. Such arrangement is highly desirable in an airplane, where the mechanism for starting may be in the cock-pit or pilot house. Likewise the boiler may be located in the fuselage and one or more turbines distributed over the ship as desired may be run from one 55 boiler. In this case only a steam pipe and a return water pipe need connect the engine unit and the boiler unit.

When the handle 30 is turned and the primary circuit closed at 36 air pump 29, 60 water pump 32 and fuel pump 33 are brought into action, and the fuel mixture thus provided in the boiler is ignited. Pressure generates in boiler 4 and since it cannot escape past the reduction valve 18 it 65 must be available at throttle 20. When throttle 20 is opened, auxiliary engine 5 starts pumps 6, 7 and 8. Pumps 29, 32 and 33 may now be stopped and the circuit at 36 be broken. As the pressure increases in 70 boiler 4, auxiliary engine 5 runs faster and faster until the pressure exceeds the predetermined pressure, and pressure operated valve 18 opens and main engine 1 and propeller 2 rotate. Water from the sump of the 75 condenser 12 is pumped by pump 7 into the boiler 4. As steam it goes from boiler 4 thru pipe 3 and valve 18 to main engine 1 from which thru exhaust pipe 13 it goes to condenser 12 and back. Some of the steam 80

goes through pipe 19 and throttle 20 to auxiliary engine 5 from which it is exhausted thru exhaust pipe 37 to exhaust pipe 13 to condenser 12 and back to boiler feed water pump 7. Obviously, pumps 6, 7 and 8 must be so calibrated as to pump correctly proportional amounts of air, water and fuel, as must pumps 29, 32 and 33.

Fig. 2 shows in section the pressure operated reduction or safety valve 18. Steam passes from boiler 4 thru pipe 3 and presses against valve 40. Spring 41 holds valve 40 against its seat until the pressure in the boiler 4 reaches a predetermined pressure at which valve 40 rises against spring 41 and steam flows thru the valve and pipe 42 to engine 1. Piston 43 acts to balance valve 40 so that the pressure on the back of valve 40 will not affect its opening.

20 I claim:

1. In a steam power plant the combination of a steam boiler, a main steam engine, an auxiliary steam engine, an air pump, a boiler feed water pump, a fuel pump, said air, water and fuel pumps operably connected to said auxiliary engine, connections from said air, water and fuel pumps to said boiler, a connection from said boiler to said main engine, a pressure operated valve on said connection to said main engine, said valve adapted to pass steam when the steam pressure in said boiler exceeds a predetermined pressure, a connection from said boiler to said auxiliary engine, a throttle valve on said connection to said auxiliary engine said throttle adapted to control said main engine by controlling the speed of said auxiliary engine determining the amount of air, water and fuel delivered to said boiler by said air, water and fuel pumps, an exhaust steam condenser, connections from said main engine and said auxiliary engine to said condenser and connection from said condenser to said water pump.

2. In an aeronautical steam power plant, 45 a steam boiler, a main steam engine, a propeller, said propeller being adapted to be rotated by said main engine, a connection for steam from said boiler to said main engine, a pressure operated valve on said connection 50 to said main engine, an exhaust steam condenser, a connection for exhaust steam to said condenser from said main engine, an auxiliary steam engine, a connection for steam from said boiler to said auxiliary engine, a throttle valve on said connection to said auxiliary engine, an air pump, a boiler feed water pump, a fuel pump, said air, water and fuel pumps being proportionately related to each other and operably connected 60 to said auxiliary engine, delivery connections to said boiler from said air, water and fuel pumps, connection from said condenser to said water pump.

3. In a steam power plant, a boiler, a main steam engine, a connection for steam from said boiler to said main engine, a pressure operated valve on said connection to said main engine, said valve adapted to permit steam to flow from said boiler to said main engine when the steam pressure on said boiler rises to a predetermined pressure, an auxiliary steam engine, a connection for steam from said boiler to said auxiliary engine, a manually operated throttle valve on 75 said steam connection to said auxiliary engine, an air pump, a boiler feed water pump, a fuel pump, said air, water and fuel pumps operably connected to said auxiliary engine and delivery connections from said air, water 80 and fuel pumps to said boiler, said manually operated throttle valve to said auxiliary engine being adapted to control said main engine by controlling the speed of said auxiliary engine, said speed being in direct ratio 85 to the amount of air, water and fuel supplied to said boiler.

WARD LEATHERS.
